UNITED STATES PATENT OFFICE.

JOHN F. BECK, OF ATLANTA, GEORGIA, ASSIGNOR OF TWO-THIRDS TO
MARY T. KINSEY AND SAMUEL W. LORD, OF SAME PLACE.

HOT-AIR DRUM.

SPECIFICATION forming part of Letters Patent No. 655,182, dated August 7, 1900.

Application filed April 24, 1899. Serial No. 714,211. (No model.)

To all whom it may concern:

Be it known that I, JOHN F. BECK, a citizen of the United States, residing at Atlanta, in the county of Fulton and State of Georgia, 5 have invented a new and useful Hot-Air Drum, of which the following is a specification.

The invention relates to improvements in hot-air drums.

10 One object of the present invention is to improve the construction of heating apparatus and to provide a simple and comparatively inexpensive hot-air drum designed to be arranged between two opposite fireplaces and 15 adapted to be heated by the fires thereof and to supply hot air to the rooms above for heating the same.

20 A further object of the invention is to provide a heating-drum of this character which 25 will be adapted to be employed in connection with any form of grate or similar apparatus.

The invention consists in the construction and novel combination and arrangement of parts hereinafter fully described, illustrated 25 in the accompanying drawings, and pointed out in the claim hereto appended.

30 In the drawings, Figure 1 is a perspective view of a heating-drum constructed in accordance with this invention and shown applied to a fireplace. Fig. 2 is transverse sectional view. Fig. 3 is a longitudinal sectional view. Fig. 4 is a perspective view of the drum detached.

35 Like numerals of reference designate corresponding parts in all the figures of the drawings.

1 designates a hot-air drum designed to be arranged between two fireplaces 3 of a wall or partition 4 in position to be heated by the 40 fires of such fireplaces to utilize the waste heat at the top and back of each fireplace for supplying hot air to the rooms above. The drum is composed of two curved upwardly-diverging sides 5, of cast metal or other suitable material, connected at their upper edges 45 by an arched top 6, of brick or other material, and the ends of the drum are closed by the side walls of the fireplaces. The sides 5 of the drum form the backs for the fireplaces 50 and separate the same, as shown in Fig. 2 of the accompanying drawings, and they present

concave outer faces and are adapted to throw the heat outward into the rooms, and thereby increase the heating power of open grates 7 or other heating devices. The arched top 6, 55 which connects the upper edges of the sides of the drum, is provided with a central opening communicating with a flue 8, extending up in the chimney 9 and adapted to conduct hot air to the rooms above. The lower edges 60 of the sides of the drum rest upon the floor or base of the fireplaces, and the lower portions of such sides are substantially parallel, and the space between them communicates with a cold-air duct 10, located beneath the 65 first floor and communicating with the outside air at any suitable point.

In order to cause the cold air to take a circuitous course through the drum, a series of horizontal baffle-plates or partitions 11 are 70 employed, and they are arranged, preferably, at regular intervals and are supported by fixed flanges or ledges 12, extending from the inner faces of the sides of the drum and cast integral or otherwise mounted thereon. These 75 horizontal plates or partitions, which extend entirely across the drum, are of less length than the same and terminate short of the ends thereof, being disposed in overlapping relation and forming alternate passages at the 80 ends of the drum. The adjacent horizontal hot-air passages have their entrance and exit openings arranged at the ends of the drum, so that the cold air entering the bottom of the drum will be caused to travel back and forth 85 from one end of the drum to the other in a serpentine course over the horizontal plates or partitions, which present a large amount of heating-surface, so that the air before it leaves the top of the drum will become highly 90 heated. The longitudinal edges of the horizontal plates or partitions may be connected with the inner faces of the sides of the drum by any suitable means; but they are preferably cemented or riveted to the horizontal 95 supporting flanges or ledges.

The invention has the following advantages: The drum, which is simple and comparatively inexpensive in construction and which is designed to be mounted between two 100 fireplaces, is heated by the superfluous heat at the back and top of such fireplaces, and it

is capable of utilizing such waste heat for heating the rooms overhead. The air, which is introduced into the drum from the outside atmosphere, is caused to travel back and forth in a circuitous or serpentine course through the drum, so that it will become heated to a high degree before it leaves the same and can be supplied to apartments above the apparatus by means of suitable flues and registers. The drum, which is adapted to be used in connection with an ordinary grate, is adapted to increase the effect of the fire by throwing the heat into the room, and the hot-air flue, which extends from the top of the drum to the apartments to be cleaned, is located within the chimney to subject the hot air to the effect of the products of combustion passing through the chimney.

The fireplace-heater of my invention is designed to be built into the fireplace at the time of building the hearth and walls of said fireplace in the course of erecting the chimney, so that the fireplace forms an integral part of the heater. The invention necessarily includes the cast-metal curved plates arranged in reverse positions, so that the upper portions thereof diverge laterally, and the upper edges terminate in the same horizontal plane, so as to form seats for the arch. The side walls of the fireplace close the ends of the hot-air chamber formed within the plates, as shown clearly by Fig. 3, and the arch 6 is built of brick, so as to span the space between the divergent ends of the metallic plates, the ends of said brick arch being seated upon the upper edges of the curved plates. A characteristic feature of my invention is the provision of the ledges integral with the plates and on the inner opposing faces thereof, said ledges being arranged in pairs, with the two edges of each pair in the same horizontal plane, thus forming supports for the horizontal baffle-plates, whereby said

plates are supported removably in place, and provision is thus made for the introduction of the plates during the course of the installation of the fireplace-heater. The masonry arch 6 is self-supporting on the curved metallic plates, and on this arch is seated the lower extremity of a single hot-air flue, which leads from the drum, in the plane of the vertical axis thereof.

It will be seen that the elements of my improved fireplace-heater mutually coact in supporting one another, because the curved metallic walls are held in place by the side walls of the fireplace, the masonry arch is upheld by the curved plates, and the hot-air flue seated on and supported by this arch. This construction and arrangement simplifies the heater as an entirety and produces a structure which may be installed at a small cost and is very efficient in operation.

What is claimed is—

In a fireplace-heater, the metallic curved plates arranged in reversed positions for their upper portions to diverge laterally and to terminate in the same horizontal plane, the ribs integral with said plates and projecting horizontally from the inner opposing faces thereof, and the masonry arched top seated upon the top edges of, and supported wholly by, the plates, combined with the fireplace-walls closing the ends of the chamber which is formed between the plates, a single hot-air flue seated upon the arch, a cold-air flue in the hearth, and baffle-plates resting on the ribs within the chamber, substantially as described.

In testimony that I claim the foregoing as my own I have hereto affixed my signature in the presence of two witnesses.

JNO. F. BECK.
